Application July 23, 1937, Serial No. 155,281

16 Claims. (Cl. 112—2)

My invention relates to automatic means for stitching upholstery material, and particularly to a method and system for combining a backing element, a pad, and trim material by multiple stitching of plaits therein.

Multi-plaiting machines have been employed heretofore for sewing plaits in upholstery pads combining a backing element, padding material and a top trim material. Methods have also been devised to obtain plait fullness in the cover material before stitching, this being accomplished before the material is disposed upon the pad. After the plait fullness was obtained in the material, it was either disposed on the pad for sewing or, on the backing element before or after the time a bat was being inserted in each of the plaits formed in this manner. The two materials were sometimes sewed together along the plait lines and the padding material was pushed, blown, or otherwise forced into the pockets formed thereby.

In practicing my present invention, I materially simplify the method of sewing pads by employing a plurality of sewing heads disposed in lateral alignment and direct the backing element, pad, and cover material through the machine to sew the materials in the same manner as any other three materials would be sewed together.

I, however, employ a unique system for forming and assembling the materials and uniting them for sewing. A backing cloth is fed upon the conveyor of a "garnetting" machine, which distributes layers of linters on the backing cloth which, upon reaching proper thickness is carried progressively through rolls to be compressed. The material is then advanced on a belt which is periodically operated to move the end of the material into a press. The press is provided with a die which stamps the pad and backing material to a predetermined size and form. The formed material is then advanced to a position to receive the top trim material which has been cut to the desired form and which is provided with pleat fullness through the operation of pivotal arms which simultaneously move into contact with the cloth to gather material along the lines to be sewed. Thereafter the material is moved onto a continuously operating conveyor chain which advances the assembly through the machine where it is sewed along the lines on which the gathering occurred.

Accordingly, the main objects of my invention are to provide a machine for compressing a backing sheet, a pad and trim material along lines which forms pleats during the time stitching occurs.

curs along said lines; to continuously feed a backing sheet and a pad to a press which simultaneously stamps out the sheet and material to predetermined size and form and delivers said material from the machine; to advance a backing sheet and pad which are stamped to a predetermined form to a position to receive a sheet of trim material and thereafter advancing the assembled elements to a position above a conveyor chain; to lower the assembled elements upon the conveyor chains after it is advanced to a position thereabove; to garnet layers of linters upon a backing sheet as it is progressively advanced to form a pad thereon, which pad and backing element is advanced to a press which stamps out sections of predetermined size and shape; to advance sections of padding and sheet material of predetermined size and shape and to place sheets of cover material thereon and to provide pleat fullness to the cover material after it is located on the sections, and, in general, to provide a pad and a method for its construction which is simple, positive and economical of manufacture.

Other objects and features of novelty of my invention will be specifically pointed out or will become apparent when referring, for a better understanding of my invention, to the following description taken in conjunction with the accompanying drawings, wherein:

Fig. 14 is an enlarged view in perspective of 10 a pressure foot employed on the sewing machine illustrated in Fig. 2.

In Fig. 1, I have illustrated a series of elements embodying a machine 15 for distributing linters or other fibers to a continuous sheet of material 16 to form a pad thereon, which sheet and pad passes through compression rolls 17 and onto a belt 19, which may sag between its supports. By using the sagging belt, intermittent feed may be had from the belt to a stamping machine 21. During the time the material is stopped after being advanced into the machine 21, a die in the machine stamps out the pad and sheet simultaneously to predetermined size and shape. A conveyor 22, operated by the mechanism of the press 21 periodically advances the stamped out units to position under a gathering device 23 for the top cover material. The sheets of material rest on a table 24 from which they are taken one at a time and placed on channel-like elements 54 and the pad. The arms of the forming device 23 cooperate with the channel elements to gather the material along the lines to be sewn. After the material has been gathered in this manner, the pad and trim materials are advanced by the conveyor 22 to a position above continuously actuated conveyor chains 25 having projecting pins which pierce the backing sheet and pad when the conveyor 22 is lowered to dispose the assembled unit upon the conveyor chains 40 25. The conveyor chains 25 continuously advance the assembled units which are further engaged by feet 26 of a sewing machine 27. The stitching of the pads by the machine occurs along the lines on which the gathering of the trim material occurred.

The garnetting of fibers upon a continuously moving sheet of backing material is illustrated and described in copending application of Clarence W. Avery, Serial No. 58,859, filed January 13, 1936, and assigned to the assignee of the present invention. The intermittent feeding device 19 is illustrated in combination with the press 21 in my co-pending application Serial No. 132,193, filed March 22, 1937, and will not, therefore, be described herein in detail.

A shaft 31 is carried by the press 21 and is driven in synchronism with the gear elements which drive the belt 19, providing intermittent operation to the conveyor 22 embodying a plurality of belts. The opposite end of the belts pass over crown pulleys 32 and idler crown pulleys 33, disposed interjacent of the belt ends. The pulleys 32 and 33 are mounted on shafts 34 and 35 respectively, which are carried on arms 36 of bell crank levers 37. The bell crank levers are connected by links 38, to a piston 39, of the hydraulic cylinder 41. Through the operation of the piston within the cylinder, the bell cranks 37 are actuated about the pivots 42, to raise and lower the shafts 34 and 35, and, therefore, the pulleys 32 and 33 carried thereby. When the belts are raised, the assembled material is lifted a sufficient height above the pins 43 on the conveyor chains 25 to prevent engagement

therebetween. When the belts are lowered, the material is disposed upon the pins 43 and the conveyor chain 25 driven at a constant speed by the sewing machine 27 moves the material from the belt and advances it through the sewing machine.

Referring to Fig. 3, I have illustrated the backing sheet 16 as having a continuous pad 44 formed thereon as the sheet continuously advances. Periodically the material is advanced into the press 21 where a die, supported by the head 45 of the press, stamps the backing sheet 16 and pad 44 into predetermined shape, that is shown at 46 in the figure. After the head 45 is raised the stamped unit 46 is advanced onto the conveyor 22 and is advanced to the gathering device 23. During the time the conveyor is at rest, that at least to permit a sufficient length of the backing sheet and pad to advance onto the conveyor 19, a sheet of covering material 47 is disposed upon the unit 46 and channel elements 54. The sheets rest upon the table 24 from which they are moved one at a time, by an operator standing at each side of the machine, to within the jaws of the gathering device. Cover positioning elements 48 are disposed at each side of the machine in which the corners of the material may be gauged by the operator to accurately locate the material. Adjacent each of the engaging elements, switches 49 are mounted in a position to be actuated by the fingers of the operator while holding the edges of the corners of the cloth in position. The four switches are connected in series as illustrated in Fig. 13 and must all be closed to operate the gathering device. This provides assurance that the hands of the operator are out of contact with the device when actuated.

Two longitudinally adjustable elements are disposed at the sides of the device in which a pair of shafts 51 and 52 disposed laterally of the device are journaled for pivotal movements. The shaft 52 supports the lower jaws or channel elements 54 while the shaft 53 supports the upper jaws 55 which are of T-shape, as illustrated in Fig. 8. The shaft 52 is provided with an arm 56 on one or both of its ends to which a spring 57 is connected to balance the weight of the lower jaws or elements 54. The channel elements 54 indent the padding material as it is advanced thereunder to cover receiving and gathering position. The cover material 47 is stretched across the unit 46 and the switches 49 actuated to operate a fluid valve which directs a flow of fluid to the cylinder 58 to actuate a piston rod 59 and link 61 secured to the end of the shaft 53. The fluid is delivered in the righthand end of the cylinder as illustrated in Figs. 6 and 7 to draw the piston rod therewithin to move the link 61 in a clockwise direction to rotate the upper jaws 55 downwardly onto the cover material. The material is drawn within the channel elements 54 disposed therebelow to provide fullness thereto. It is to be understood that the formation of the padding material and the gathering of the cover material occurs along lines aligned with the sewing heads of the multi-stitching machines. That is to say, the pad and cover material is pre-formed and provided with pleat fullness, respectively, along lines at which the stitching occurs. Upon the release of the switches 49, fluid is directed into the opposite end of the cylinder 58 for moving the piston rod 59 outwardly to thereby rotate the shaft 53 along with the upper jaws 55 in a counter-clockwise direction to a position illustrated in Fig. 7. Thereafter, the conveyor

22 is raised and the assembled and formed unit is carried to a position over the continuously moving conveyor chains 25. At the end of advancement of the conveyor 22, the cylinder 41 is energized to actuate the bell cranks 37 to lower the pulleys 32 and 33 and, therefore, the conveyor 22 to deposit the assembled unit upon the conveyor chains 25. The pins 43 of the chains project through the backing material into the padding material and advance the assembled unit toward the sewing machine 21. Each time the shaft 31 is rotated to advance the conveyor 22, the cylinder 41 is energized to operate the bell cranks to raise the pulleys 32 and 33 to thereby raise the conveyor before it advances. In this manner the backing sheet and pad is continuously moved as the pad is formed and is intermittently moved into and from the press and the gathering and forming device and is continuously moved thereafter through the sewing machine, all in timed relation with each other.

The conveyor chains 25 are disposed between the heads 61 of the sewing machine to permit the looper needles to be operated directly under the sewing needles. The pressure feet 26 attached to each of the heads 61 are illustrated enlarged in Fig. 14. The feet comprise a casting 62 having an upwardly projecting portion 63 by which the castings are secured to the sewing heads by suitable means not here illustrated in detail. A pair of sprockets 64 are journaled on a shaft (not shown) of the sewing machine 21, which shaft is journaled in the casting 62. Sprocket wheels 65 are mounted at the front end of the casting on shafts journaled in a bearing 66 which is adjustable by a screw 67. The front end 68 of the casting is sloped upwardly to receive the assembled material which is thereafter engaged by chains 69 which are disposed on each side of the casting over the sprockets 64 and 65 at opposite ends thereof.

The outer surface of the links and plates of the chains are serrated at 71 to prevent slippage from occurring between the chains and the engaged material. The chains are guided in downwardly projecting slots in the side plates 72, the slack, return portion of the chains pass under the blocks 73 and 74 containing grooves which receive the chains. An opening 75 is provided in the casting through which a needle 76 operates to stitch the material compressed and moved by the foot 26. The chains 25, as pointed out hereinabove, are driven from the sewing machine, which driving occurs in timed relation with the operation of the chains 69. The chains 25 have the sprockets 64 thereof driven by a common shaft 40, while the chain 69 has the sprocket 65 thereof driven by a common shaft 70. The shafts 40 and 70 are interconnected by a pair of gears 100, which are similar, to have the shafts driven at a constant speed. This produces the constant driving relation between chains 25 and 69. The operation of both sets of chains in this manner makes certain that the material moves through the sewing machine without the elements thereof slipping relative to each other.

Outwardly of the sewing heads 61 and feet 26, a pair of engaging and advancing feet 77, similar to the feet 26, are mounted directly over the outer conveyor chains 25. The feet are illustrated enlarged in Figs. 9 and 10 and embody a casting 79 which is secured to a cross-bar 81 of the machine 21 by a stud 82 by which the feet are adjusted in height relative to the material. The shaft of the sewing machine which 75

drives the sprocket 64 of the foot 26 is also journaled in the casting 79 and also drives a sprocket 83 which is mounted on the foot 77. A sprocket chain 84 is mounted over the sprocket wheel 83 and is guided in a channel 85 in the bottom of the casting 79 which likewise slopes upwardly at its front end. An adjustable sprocket 86 is mounted on the front end of the shoe and tensions the under portion of the chain, the slack or return portion of the chain being encompassed by suitable guide plates 87 and 88. The chain 84 is provided with a plurality of outwardly projecting pins 89 which positively engage the cover material and pad above the pins in the chains 25 which engage the backing sheet and underportion of the pad. The feet 77 aid the outer chains 25 to advance the side edges of the assembled material as the stitching occurs interjacent thereof.

20 Through the use of the feet 26 and 77 in combination with the conveyor chains 25 assurance is had that the units advance uniformly through the sewing heads 61 without any shifting of the elements which make up the units. Since the 25 operation is continuous, the pads passing through the machine will be connected together by threads which are united as the machine continues to operate until the next adjacent unit passes thereinto. As the units pass from the machine the threads joining the pads are cut and the 30 operation is completed.

Referring to Figs. 11 and 12, I have illustrated the outer end of the gathering device 23 wherein in the end of the gathering jaw 55 has a guide 35 91 associated therewith which is adjustable vertically relative thereto by a stud 92. A V-shaped body portion 93 is provided on the adjusting device 91 which is dimensioned to be recessed within the channel element 54 to thereby locate the lower edge of the blade 25 with the bottom of the channel element. In this manner, the amount of material drawn into the channel element is regulated to thereby regulate the size of the plait to be formed.

45 In Fig. 13, I have illustrated a wiring diagram wherein the plurality of switches 49 are illustrated in series relation with a circuit 94 connected to a solenoid 95. The solenoid operates a fluid valve 96 which controls the flow of fluid to and from the cylinder 58 which operates the gathering device. Since the two hands of each of the operators must be employed for operating the switches, the arrangement provides a safety factor preventing the hands of the operator from 50 being disposed between the gathering device when the device is moving downwardly.

It will thus be seen that my method of constructing pads is continuous, embodying the feeding of a continuous sheet of backing material 60 uniformly across the conveyor of a "garnetting" machine where a pad of unwoven fiber material is disposed. After the pad is compressed through rollers, it is intermittently fed while stamped into units of predetermined size and form which 65 are further advanced intermittently to the gathering device where a sheet of covering material is placed thereon and gathered along the lines to be sewn. The material is further intermittently advanced to a position over continuously operating conveyor chains where it is disposed to be uniformly advanced through the sewing machine. The various feed mechanisms are interconnected to provide synchronized movements, and, except for the use of the operators for placing the cover material upon the units, the op-

eration is entirely automatic. The pads made in this manner are accurate of form, positively sewn and economical of manufacture.

Formal changes may be made in the specific embodiment of the invention described without departing from the spirit and substance of the broad invention, the scope of which is commensurate with the appended claims.

I claim as my invention:

1. A method of constructing a pad embodying the steps, of continuously feeding a backing sheet and padding material, of die stamping units therefrom, of applying a cover material to each of the units, of forming fullness in said cover material, and sewing the unit and material along predetermined lines.

2. A method of constructing a pad embodying the steps, of continuously feeding a backing sheet and padding material, of cutting units therefrom, of applying a cover material to each of the units, and sewing the assembled material along predetermined lines.

3. A method of constructing a pad embodying the steps, of continuously feeding a backing sheet and padding material, of intermittently feeding said sheet and material, of severing portions therefrom, of intermittently advancing said severed portions, of disposing covering material on said severed portions, and continuously feeding said assembled materials through a machine to secure the materials together at predetermined points.

4. A method of constructing a pad embodying the steps, of continuously feeding a backing sheet and padding material, of intermittently feeding said sheet and material to have units cut therefrom, of intermittently advancing said units, of placing a cover material on said unit, of continuously feeding said assembled materials through a sewing machine and of stitching said materials together along predetermined lines.

5. A method of constructing a pad embodying the steps of severing a unit from a pad and backing sheet, of applying a cover material to said unit, of forming fullness in said material along predetermined lines, and sewing said material and unit together along said lines.

6. A method of constructing a pad embodying the steps of severing a unit from a pad and backing sheet, of applying a cover material to said unit, of depressing said pad along predetermined lines, of gathering said material to provide fullness along said lines, and stitching said material and unit together along said lines.

7. A method of constructing a pad embodying the steps of continuously feeding a backing sheet and padding material, of stamping units of predetermined form therefrom, of depressing said padding material of said units along predetermined lines, of applying a cover material to each of the units, of forming fullness in said cover material, and sewing the units and material along said lines.

8. A pad forming device including, in combination, means for continuously feeding a backing sheet, means for continuously forming a pad thereon as the sheet is advanced, a die intermittently receiving said sheet and pad for stamping units therefrom, means for gathering fullness in a cover material disposed on said units and means for stitching said units and material together.

9. A pad forming device including, in combination, means for continuously feeding a backing sheet, means for continuously forming a pad thereon as the sheet is advanced, means for in-

termittently advancing said sheet and pad, a die for blanking out a unit after each advancement, means for intermittently advancing said unit to depress the pad along predetermined lines, a cover material, means for gathering fullness in said cover material after it is disposed on said unit, and means for stitching said material and unit together.

10. A pad forming device including, in combination, means for advancing a backing sheet having a pad thereon, means for stamping out units from said pad and backing sheet, means for gathering fullness in a cover material and means for stitching said material and unit together.

11. A pad forming device including, in combination, means for advancing a backing sheet having a pad thereon, means for stamping out units from said pad and backing sheet, means for gathering fullness in a cover material after it is disposed on said unit, conveyor chains for advancing said assembled elements, a sewing machine, and pressure means for compacting said elements and feeding the elements through said machine.

12. A pad forming device including, in combination, a sewing machine having a plurality of spaced heads, a bed, conveyor chains on said bed, one disposed between each of said heads, and pressure feet having conveyor chains thereon disposed above said bed, each supported individually on one of said heads.

13. A pad forming device including, in combination, a sewing machine having a plurality of spaced heads, a bed, conveyor chains on said bed disposed between said heads on each side of the outermost heads, a pressure foot supported individually on each of said heads above said bed between said chains, said pressure feet having conveyor chains thereon.

14. A pad forming device including, in combination, a sewing machine having a plurality of spaced heads, a bed, conveyor chains on said bed disposed between said heads on each side of the outermost heads, a pressure foot supported individually on each of said heads above said bed between said chains, said pressure feet having conveyor chains thereon, and means for driving all of said chains in timed relation.

15. A pad forming device including, in combination, a conveyor for intermittently advancing a plurality of superposed elements forming a unit to be stitched, a continuously moving conveyor overlapping said first conveyor, means for relatively raising and lowering said conveyors to permit the intermittent advancement of said unit out of engagement with said second conveyor and for thereafter disposing said unit upon said second conveyor, a sewing machine, and means for continuously advancing said second conveyor through said sewing machine.

16. A pad forming device including, in combination, a conveyor for intermittently advancing a plurality of superposed elements forming a unit to be stitched, a continuously moving conveyor overlapping said first conveyor, means for relatively raising and lowering said conveyors to permit the intermittent advancement of said unit out of engagement with said second conveyor and for thereafter disposing said unit upon said second conveyor, a sewing machine, heads on said machine disposed between the elements of said second conveyor and pressure feet on said heads cooperating with said elements for moving said unit through said machine.

ALFRED H. HABERSTUMP.
